UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

STEAM-HEATING SYSTEM.

1,172,376.

Specification of Letters Patent. Patented Feb. 22, 1916.

Application filed June 18, 1912. Serial No. 704,396.

To all whom it may concern:

Be it known that I, JAMES F. McELROY, a citizen of the United States, residing at Albany, county of Albany, State of New York, have invented certain new and useful Improvements in Steam-Heating Systems, the following being a full, clear, and exact disclosure of the one form of my invention which I at present deem preferable.

10 For a detailed description of the present form of my invention, reference may be had to the following specification and to the accompanying drawings, which illustrate my invention, wherein—

15 Figure 1 is a perspective showing the fundamental principle of my system; Figs. 2 and 3 are fragmentary detail views showing the different conditions of the shift valve; Figs. 4 to 9 inclusive are detail views showing in 20 section and elevation the practical construction and arrangement of vapor and pressure traps suitable for my system; Fig. 10 is a perspective view, and Figs. 11 and 12 are fragmentary detail views showing the 25 mode of splitting my series-multiple system for two sides of a car; Figs. 13, 14, 15 are views similar to Figs. 10, 11 and 12 showing a split and duplicated arrangement of 30 my series-multiple system for larger and more flexible heating requirements.

My system is designed to operate either as a vapor or pressure system and the radiator pipes therefor are divided into sections which are connected in series with 35 each other for vapor heating and in multiple for pressure heating. I also place the pressure trap at the point of junction of the two pipe sections which are both connected with the screen chamber of the trap, 40 whereby under the series arrangement the steam will sweep through that chamber and clear the dirt therefrom, which would tend to accumulate therein under the multiple arrangements. For lesser heating requirements, as in modern cars, I split the piping, placing the respective pipe-sections on opposite sides of the car, while for greater heating requirements, as in steel cars, I both split and duplicate the piping for securing 45 not only a greater total of heating effect, but also more degrees of regulation by changing from vapor to pressure conditions in the several sections.

Referring to Fig. 1 the train pipe or

source of steam supply is shown at T. The 55 radiator piping is divided into two parts or sections, the pipes in the first section being marked *a* and those in the second section being marked *b*. The inlet from train pipe T to the radiator is by the lead pipe 1 60 which conducts the steam to the vapor trap (containing the inlet valve controlled by the trap) from which the pipe 2^a leads to the first pipe section comprising pipes *a* and the pipe 2^b (communicating with the 65 thermostat-chamber of the trap) leads to the second section comprising the pipes *b*. The two sections are joined at the pressure trap P to which they are connected by the respective pipes 4^a and 4^b. It should be 70 understood that the short section of pipe marked 5 between train pipe T and the pressure trap P is not a part of the circulating system but merely a pipe for the local external heating of the trap by the train 75 pipe. These two pipes 4^a and 4^b enter the trap on opposite sides of the screen chamber of the trap and, when the two sections are in series, the flow of steam through the chamber will sweep out the dirt which 80 tends to accumulate therein when the sections are in multiple and the trap forms the terminal of the system. Thus, Figs. 6, 7 and 9 show the pressure trap in detail, the screen-chamber thereof being shown at G 85 and the screen at S. The thermostat M of the trap (it is contained in an open cage W from which water can escape) will operate the outlet valve K by means of the stem R in the usual manner to control the outflow of water of condensation from the chamber G to the thermostat and the outer air, whenever the system is set for pressure 90 operation. The steam (under vapor conditions) will enter chamber G by pipe 4^a and 95 depart therefrom by pipe 4^b.

In Figs. 4 and 5 are shown the vapor trap V wherein, as is well known, the outflow of water of condensation from the radiator pipe (which has in most cases a free outlet to the atmosphere at atmospheric pressure) is delivered on the exposed thermostat which, in accordance with the temperature, regulates the inflow of steam to the radiator from the train pipe, in contrast to the pressure trap, which regulates the outflow of water of condensation from the radiator at the outlet end thereof. In the vapor trap

V, the live steam from train pipe T arrives, by lead pipe 1, in the chamber E (see Fig. 4) whence it passes through regulating valve D into chamber E¹ from which it goes by pipe 2^a (see Fig. 5) to the radiator, the said valve D being governed by the thermostat C by means of the rod H and lever J in the well known manner. The pipe 2^a communicates with the thermostat chamber F (see Fig. 4), so that, when the two radiator sections are in series, the regulated inflow of live steam to the radiator by pipe 2^a will return as water of condensation by pipe 2^b to the vapor trap.

15 To convert the system to a vapor or a pressure system, I place a 3-way shift-valve A in the pipe 2^b and at the same point a cross pipe 3 is extended from pipe 2^a to pipe 2^b as shown in Fig. 1. This valve A may be turned, as shown in Fig. 2, to permit a free flow along pipe 2^b and blank the cross pipe 3; or it may be turned, as shown in Fig. 3 to cross connect pipes 2^a and 2^b and blank the connection of pipe 2^b with vapor trap V. In the former case the system will be a vapor system and in the latter case a pressure system. Considering the first case, it is manifest that the steam will flow from the train pipe T, by lead pipe 1 to chamber E of the trap V, and then through regulating valve V to chamber E¹ and out through pipe 2^a to the first section of the radiator comprising pipes a to the pressure trap P, and after passing through the screen-chamber G of that trap will flow through the second section of the radiator comprising pipes b back to the vapor trap V, where it enters, by pipe 2^b, the thermostat chamber F of that trap. The radiator sections will then be in series and the system will operate in the well known "vapor" fashion. Considering the second case, the steam will flow from the train pipe T, by lead pipe 1 to chamber E of trap V; and since the valve D will in this case remain wide open and inactive (because its thermostat is cut-off from the system) the steam will flow freely from chamber E to chamber E¹ and thence by pipe 2^a to the cross pipe 3, where it branches, one half going by said pipe 2^a to the first radiator section comprising pipes a, and the other half going by pipes 3 and 2^b to the second radiator section comprising pipes b. The two branch streams will reunite at the screen-chamber G of the pressure trap P, and if the two streams have lost enough heat to be condensed to water and the water is cold enough, it will find valve K open and pass therethrough to the thermostat M and the outside air. This water being soon followed by warmer water, or even by steam, the thermostat will become heated and will act to close valve K. This is the well known operation of a pressure system. In such a system, since the radiator outlet is under control, the steam pressure in the radiator will be raised and a greater heating effect will result, whereas in the vapor system the radiator outlet is or may be wide open 70 to the atmosphere and the pressure in the radiator will be but atmospheric pressure or nearly so, the heating effect being less. It will be noted that the trap P automatically changes the pressure within the radiator in accordance with the operation of valve A. Said trap controls the system when operating as a pressure system and I therefore term it a pressure trap. Likewise the trap V controls the system when operating as a vapor system and I accordingly term the same a vapor trap.

16 The method of piping by dividing the heating apparatus into two parts and placing the pressure trap between these two parts and remote from the point of inflow of steam removes the necessity for connecting the large heating pipes into a rigid system of piping which does not provide for expansion of the pipes and enables the radiating pipes to be constructed without offsetting at the ends of the car which is necessary with other modes of piping.

17 Figs. 10, 11 and 12 show the splitting of the system to bring the respective radiator sections on opposite sides of a car. Under vapor conditions the steam will go first to one side of the car and back to the pressure trap, which will be closed as soon as the water condensed in this initial heating of 95 the first section of radiator has been discharged through the trap. Then the steam will resume its flow into the second radiator section on the opposite side of the car and ultimately reach the vapor trap and initiate 100 the regulating action of the vapor-trap thermostat on the inlet valve by which the steam first passed from the train pipe to the first radiator section. Under pressure conditions the steam will flow simultaneously to 105 both radiator sections which are then in multiple instead of series.

18 In Figs. 13, 14, 15 and also in Fig. 8 I have shown both a splitting of the radiator pipes in multiple between the two sides of 115 the car and a duplication of such a split arrangement. The respective pressure traps are shown at P and P¹ and the respective vapor traps at V and V¹. The pipes of the respective sets are marked by corresponding 120 letters and both, it will be observed, can be converted into either pressure or vapor systems and in either or both conditions the heating will be uniform throughout the car. Thus for one degree of heat a single set of pipes will be used as a vapor system and for a second degree of heat will be shifted to a pressure system. For the third degree of heat both sets will be put under vapor 125 conditions and for the fourth degree of heat 130

both sets will be put under pressure conditions, while in all four cases the radiator will be operating at its highest efficiency.

What I claim as new and desire to secure by Letters Patent is:

1. A heating system comprising a radiator divided into distinct sections, a supply pipe, means for selectively connecting said sections with said supply pipe in series or in multiple, and automatic means for varying the pressure in said sections to conform to the connection selected.
2. A heating system comprising a radiator divided into distinct sections, a supply pipe, means for selectively connecting said sections with said supply pipe in series or in multiple, and automatic means connecting said radiator sections for effecting variations in the pressure in said sections to conform to the connection selected.
3. A heating system comprising a radiator formed of independent coils, a supply pipe, means for selectively connecting said coils with said supply pipe in series or in multiple, and automatic means for varying the pressure in said sections to conform to the connection selected.
4. A heating system comprising a radiator divided into distinct sections, a supply pipe, means for selectively connecting said sections with said supply pipe in series or in multiple, and a pressure trap connecting said radiator sections and provided with automatically operated means for effecting variations in the pressure in said sections to conform to the connection selected.
5. A heating system comprising a radiator divided into distinct sections, a supply pipe, a vapor trap controlling the passage of steam from said supply pipe, means for selectively connecting said sections with said supply pipe in series or in multiple, and a pressure trap connecting said radiator sections and provided with automatically operated means for effecting variations in the pressure in said sections to conform to the connection selected.
6. A heating system comprising a radiator divided into distinct sections, a supply pipe, means for selectively connecting said sections with said supply pipe in series or in multiple, and a pressure trap connected to the ends of the radiator sections remote from the source of supply, and provided with automatically operated means for effecting variations in the pressure in said sections to conform to the connection selected.
7. A heating system comprising a radiator divided into distinct sections, a supply pipe, means for selectively connecting said sections with said supply pipe in series or in multiple, a vapor trap between said supply pipe and a source of steam supply, and a pressure trap connected to the opposite

end of said sections and provided with automatically operated means for effecting variations in the pressure in said sections to conform to the connection selected.

8. A heating system comprising a radiator divided into distinct sections, a supply pipe, means for selectively connecting said sections with said supply pipe in series or in multiple, a vapor trap provided with a regulating valve and a thermostat chamber for controlling the passage of steam to said supply pipe, and a pressure trap connecting the sections at their other ends, and provided with automatically operated means for effecting variations in the pressure in said sections to conform to the connection selected.

9. A heating system having its radiator pipes divided into distinct sections, a vapor trap provided with a valve chamber having a regulating valve, said trap being provided with a thermostat chamber having means for controlling said valve, means for selectively connecting the inlet ends of said sections with the valve chamber of the vapor trap, or connecting said inlet ends respectively to the valve chamber and to the thermostat chamber of the vapor trap, and a pressure trap connecting the outlet ends of said radiator sections and provided with automatically operated means for effecting variation in the pressure in said sections to conform to the connection selected.

10. A steam heating system having its radiator pipes divided into distinct sections, a pressure trap having a screen chamber to which the sections are connected at their outlet ends, and a vapor trap having a valve chamber to which the inlet end of one of the sections is connected, a thermostat chamber to which the inlet end of the remaining section is connected, means for connecting the inlet end of the last mentioned section with said valve chamber, and a valve selectively controlling the passage of steam to or from the inlet of said last mentioned section.

11. A steam heating system having its radiator pipes divided into distinct sections, a vapor trap controlling the steam supply at the inlet ends of said sections, a pressure trap connected to the outlet ends of said sections, and means for selectively connecting said sections and the vapor trap in series for vapor heating, or said sections and the pressure trap in multiple, said pressure trap having automatically operated means for effecting variation in the pressure in said sections to conform to the connection selected.

12. A steam heating system having its radiator pipes divided into distinct sections, a vapor trap having a valve chamber connected to the inlet end of one section, and a thermostat chamber connected to the inlet end of the other section, means for selec-

tively disconnecting the inlet end of the last mentioned section from said thermostat chamber and connecting it to the source of steam supply, and a pressure trap connecting the outlet ends of said radiator sections and provided with automatically operated means for effecting variations in the pressure in said radiator to conform to the connection selected when said disconnecting means is operated.

13. A steam car heating system comprising radiator pipes divided into distinct sections, means for supplying steam to said radiator pipes, said means including a vapor trap provided with a thermostat chamber, a pressure trap provided with a receiving chamber, and means for passing steam through the sections in series to the thermostat chamber of the vapor trap, or through

said sections in multiple to the receiving chamber of the pressure trap.

14. A heating system comprising a radiator divided into distinct sections located on opposite sides respectively of the chamber to be heated, a supply pipe, means for selectively connecting said sections with said supply pipe in series or in multiple and automatic means for varying pressure in said sections to conform with the connections selected.

In witness whereof I have hereunto set my hand, before two subscribing witnesses, this 13th day of June, 1912.

JAMES F. McELROY.
